ATTY.

UNITED STATES PATENT OFFICE.

PETER CAMERON, OF METHIL, SCOTLAND.

SPRAYING AND DISTRIBUTING NOZZLE.

1,415,523.

Specification of Letters Patent. Patented May 9, 1922.

Application filed January 3, 1920. Serial No. 349,261.

To all whom it may concern:

Be it known that I, PETER CAMERON, of "Briar Lea," Methil, in the county of Fife, Scotland, a subject of the King of Great Britain and Ireland, have invented certain new and useful Improvements in or Relating to Spraying and Distributing Nozzles, (for which I have obtained British Letters Patent No. 141,772, dated December 17, 1918,) of which the following is a specification.

This invention relates to spraying nozzles in which one or more of the streams of fluid are discharged spirally to meet another stream in a chamber from which they issue together. The object of this invention is to provide an improved nozzle which can be used with the same or different fluids.

According to this invention I provide two or more separate inlets which can be used for the same or different fluids.

In one manner of carrying out the invention the device is provided with a disc having orifices cut in its periphery at an angle transversely to the main axis of the nozzle. At the central portion of the disc other orifices are formed at a transverse angle to the main axis of the nozzle and in an opposed direction to the orifices in the periphery. Between the two streams another stream issues through orifices parallel to the axis of the nozzle. In front of the disc is a coned or tapered chamber terminating in a discharge aperture which forms the nozzle. The streams of fluid passing through the apertures strike the sloping walls of the restricted space within the chamber and thus react upon each other, the impact causing the particles of fluid to become finely divided and thoroughly atomized.

If preferred the peripheral orifices may be cut at an angle as above described and the central orifices may be formed parallel to the main axis of the nozzle. In this case also a third stream of fluid is directed between the two whirls of fluids so formed and the streams of fluid having passed through the orifices will strike the walls of the restricted space and so become thoroughly atomized.

The details with regard to the cross-sectional area of the orifices and the manner of securing and turning the main disc, may be applied to this invention as described in my prior patent above referred to.

If desired the nozzle may be employed for the combining of two or more fluids before discharged through the nozzle, in which case a passage would conduct fluid to the peripheral orifices and a separate passage would conduct fluid to the central orifices, or one fluid will be conducted to the central and peripheral orifices and the other to the intermediate orifices. The number of fluids which may be mixed being, within reason, unlimited, it only being necessary to supply a separate set of orifices and passages for each particular fluid.

In some cases I may employ a solid mixed with the fluid, such as sand, for use as a sand blast, or I may mix the ingredients of whitewash with the fluid for whitewashing walls and the like.

Referring to the drawings filed herewith:

Fig. 1 is a longitudinal section of one form of spraying nozzle made in accordance with this invention; and

Fig. 2 is a section on the line 2—2 in Fig. 1.

The nozzle comprises an external tube *a*, an internal tube *b*, and an intermediate tube *c* forming a central passage and two annular passages. The external tube is provided with an inlet *d*, and the external tube *a* and the internal tube *b* are connected by ports *e e*.

The internal pipe *b* is closed by a plug *f* and the external tube *a* is closed by a cap *g* which is provided with a threaded socket *h* for connection with a pipe supplying tar, oil or other fluid to be sprayed. The external tube is provided with an annular plug *j* and the internal tube with a plug *k*. The plug *j* is pierced with inclined or helically disposed ports *m* and the plug *k* is pierced with ports *n* inclined in the opposite direction to the ports *m*. The end of the nozzle is provided with a conical extension forming a chamber *o* having an orifice *p*, the plugs *j* and *k* forming partitions between the tubes *a* and *b* and the conical chamber *o*.

In use, when it is desired to spray oil, tar, paint, or other liquid, the socket *h* is connected to the liquid supply, under pressure or otherwise, and the orifice *d* is connected to compressed air or steam supply. The compressed air or steam passes into the outer and inner tubes and issues through inclined holes or jets *m* and *n* causing swirls in opposite direction. The liquid to

be sprayed is drawn into or forced into the chamber *o* with the steam or air and is forced out through the orifice *p* in a fine and evenly distributed spray.

5 This invention is adapted for use in burning liquid and pulverized fuel of all description.

What I claim and desire to secure by Letters Patent is:—

10 A nozzle comprising a plurality of concentric tubes forming a central passage and two annular passages, a conical extension car-

ried by the external tube, partitions between said extension and two of said tubes, said partitions having a plurality of oppositely disposed helical ports communicating with said extension and tubes, transfer ports communicating with the outer and central passages, said annular passages each having an inlet and said extension being provided with an outlet orifice.

In testimony whereof I have signed my name to this specification.

PETER CAMERON.
